[57] ABSTRACT

A thin film microwave iris including an aperture, inside a microwave waveguide transverse to the flow of microwave energy in the waveguide with the thin film electrically connected to the walls of the waveguide. Due to the flow of energy through the film as well as through the aperture, the characteristics of thin film irises are different from the characteristics of conventional irises.

THIN FILM MICROWAVE IRIS

ORIGIN OF THE INVENTION

The invention described herein was made in the performance of work under a NASA contract and is subject to the provisions of Section 305 of the National Aeronautics Space Act of 1958, Public Law 85-568 (72 stat. 435, 42 U.S.C. 2457).

BACKGROUND OF THE INVENTION

The invention relates generally to irises in microwave waveguides and more specifically concerns a thin film iris including an aperture therein in microwave waveguides.

"Thin film" as used in this specification and claims include all film thicknesses for which a detectable power transmission through the film can be measured provided that the thickness of the film is negligible when compared to the waveguide wavelength of the microwave signal. To be more specific, in the case of all metal and semimetal films, thin film includes all film thickness of less than 1,000 angstrom units even though the thickness can be of several thousand angstrom units and still meet the definition. Low conductivity semiconductors, on the other hand, could require thickness on the order of wavelength and therefore can not be considered as "films." High conductivity semiconductors may be on the order of tens of thousands of angstroms in thickness and satisfactorily meet the requirement of being a thin film.

The recent introduction of thin conducting films into the fabrication of microwave devices opens a new area of research and development. Because thin conducting films have a finite conductivity (as contrasted to the almost perfect conductivity of most bulk metals) they can support an electric field. Thus, the conventional boundary condition that the tangential component of electric strength is zero at a conducting surface does not apply to these films with their finite conductivity.

In a conventional iris the flow of energy is only through the aperture whereas in a thin film iris there is flow of energy through the thin film as well as through the aperture. Also, there is a finite electric field over the surface of the thin film iris. These properties of the thin film iris cause it to have characteristics different from the characteristics of a conventional iris. The power transmission through the thin film iris is dependent on the thin film conductivity times the film thickness, and on the shape and size of the aperture in the film. A thin film iris can be designed to present either an inductive or a capacitive reactance. A rectangular aperture, which is normally inductive in conventional irises, may be capacitive under predictable conditions in the thin film iris. Elliptical apertures in thin films do not display capacitive reactances provided the minor axes of the ellipses are kept relatively small, and are oriented less than 45° from a parallel to the narrow wall of the waveguide.

SUMMARY OF THE INVENTION

The invention includes a thin film in a waveguide with the edges of the thin film connected electrically to the walls of the waveguide. A small aperture is cut in the film to control the power transmission through the film. The shape of the aper-

ture can be either circular, rectangular or elliptical and be made either capacitive, inductive or resistive by merely changing the size of the aperture.

BRIEF DESCRIPTION OF THE DRAWING

The sole FIGURE in the drawing is a schematic drawing of the preferred embodiment of the invention.

DETAILED DESCRIPTION OF THE INVENTION

Turning now to the embodiment of the invention selected for illustration in the drawing the number 11 designates a microwave waveguide. A thin film 12 is deposited on a thin mica substrate and located in waveguide 11 transverse to the flow of energy through the waveguide. Mica substrates several thousandths of an inch in thickness are transparent and do not reflect microwaves. Thin film 12 is connected electrically to the walls of waveguide 11 by suitable means such as conducting silver paint 13. An elliptical aperture 14 is cut in thin film 12. In alternate embodiments of the invention rectangular aperture 15 and circular aperture 16, both shown by dotted lines, can be substituted for elliptical aperture 14.

Measurements have been made on the thin film irises with elliptical apertures. These measurements show that an iris is inductive until the major axis becomes large with respect to the minor axis then it becomes capacitive. Hence by merely changing the major axis relative to the minor axis of the elliptical aperture of a thin film iris the iris can be made inductive, resistive or capacitive.

Measurements have also been made on thin film irises with rectangular apertures. These measurements show that an iris is capacitive provided the minor axis is kept relatively small. Then as the minor axis of the aperture is made larger the iris displays an inductive reactance. Hence the rectangular aperture too can be changed in size to cause the thin film iris to be capacitive, inductive or resistive. Similar measurements have been made on a thick foil iris of identical dimensions with the rectangular aperture being varied in the same way that it was varied in the thin film measurements. These measurements show that a thick foil iris exhibits a positive or an inductive reactance at all times and never becomes capacitive. Consequently, the thin film iris with a rectangular aperture has the advantage over a similar foil iris with a rectangular aperture in that it can be made to exhibit either a capacitive, inductive or resistive impedance to the flow of microwave energy through the waveguide while the foil iris remains inductive.

The advantage of this invention is that it is adaptable to more applications than previous microwave irises.

What is claimed is:

1. A thin film microwave iris for a waveguide comprising: a thin film of conducting material inside said waveguide transverse to the flow of microwave energy inside said waveguide; said film being of such thickness as to both transmit and obstruct a substantial portion of the incident microwave energy; and an aperture in said thin film whereby the impedance of said thin film can be made inductive, capacitive or resistive by changing the size of said aperture and whereby the impedance properties of said iris is substantially different than that of a geometrically similar iris in a thick conductive diaphragm.
